UNITED STATES PATENT OFFICE.

HIRAM S. HARRIS, OF CINCINNATI, OHIO.

GATE.

SPECIFICATION forming part of Letters Patent No. 395,827, dated January 8, 1889.

Application filed October 18, 1888. Serial No. 288,417. (No model.)

To all whom it may concern:

Be it known that I, HIRAM S. HARRIS, of Cincinnati, in the county of Hamilton and State of Ohio, have invented new and useful 5 Improvements in Gates, of which the following is a full, clear, and exact description.

My invention relates to sliding gates of that class operated by levers actuated by persons passing the gateway; and the invention has 10 for its object to provide simple, inexpensive, and positively-acting devices by which the gate may be slid open or shut easily and without derangement of the levers, pull-cords, and drum.

15 The invention consists in certain novel features of construction and combinations of parts of the gate-operating devices, all as hereinafter described and claimed.

Reference is to be had to the accompanying 20 drawings, forming a part of this specification, in which similar letters of reference indicate corresponding parts in all the figures.

Figure 1 is a perspective view of a gate embodying my improvements, one pair of the 25 operating-levers being partly broken away. Fig. 2 is a detail perspective view of the gate-operating drum, with its shaft and sprocket-wheel connections and portions of the gate-operating cords; and Fig. 3 is a perspective 30 view of the cord-guide at the main gate-post.

The gate proper, A, shown is formed of uprights, rails, and braces; but it may have any ordinary or approved construction. It is fitted to slide between two uprights, b b, constituting, with a cap-piece, the main gate-post 35 B, and is adapted to close to the latch-post C and to open to or toward a post, D, of the adjacent fence-panel. The gate is provided at its inner end with a couple of anti-friction 40 rollers, a a, which travel upon a guide rail or rod, E, fixed to the posts B D, and a couple of anti-friction rollers, a' a', are provided on the post B for the top rail of the gate to move between, while the lower gate-rail has support 45 at all times on a roller, a², journaled to and between the lower ends of the uprights b b of the post B, and when the gate is closed across the roadway F its bottom rail rests on a roller, a³, journaled to a block of wood or stone set 50 about at the center of the roadway and out of the path of wheels of vehicles passing the gateway.

To and between the uprights of the main gate-post B is journaled a drum, G, the shaft 55 g of which carries at each end a sprocket-wheel, H, under which runs the bight of a chain belt, I, the opposite ends of which are coupled to the inner ends of two levers, J K, which are fulcrumed by a pin, j, to the outer ends of a cross bar or head, L, which is fixed 60 to the top of the post B. There are a pair of levers, J K, extending along the gateway at and from each side of the post, and each lever is provided at its outer end with a pull chain or cord, k, by which it may be drawn 65 upon by a person on a vehicle or on horseback traveling along the roadway to open and close the gate, as hereinafter explained. A guard-plate, M, having a flange, m, by which it is attached by screws or bolts to the post B, 70 is provided under each sprocket-wheel H, to prevent disengagement of the chain belt therefrom.

I employ two gate-operating cords, N O, the former being connected at one end to the 75 drum G by passing it through a hole, n, at the drum-flange and knotting it outside the drum, and after being turned a few times around the drum this cord N is connected to an eye or loop on a stirrup iron or shackle, n', at the 80 back end of the gate. The cord O is connected at one end in like manner at o to the drum, and after being wound upon the drum a few times in the reverse direction to the cord N it is connected at its outer end to one 85 arm of an elbow-lever, P, which is fulcrumed at the top of the outer end of the gate, and is connected by a link or rod, p, with the elastic latch R, which is held at its inner end to one of the gate-rails, and at its outer end has a 90 hook-shaped head, r, which is adapted to engage or latch automatically behind a pin, S, fixed in the post C, as the gate closes.

A V or U shaped wire or metal rod, T, is arranged horizontally in the slot of post B between the gate and drum and contiguous to the latter—that is to say, its body or looped portion t is thus arranged, and is secured in such position by fastening its laterally-bent ends t' to the post. 95

The function of the device is to prevent the cords from slipping off the drum when pulled by design or accident.

It is obvious that a person approaching the

closed gate from either side of it may by pulling the chain or cord *k* of a lever, *J*, raise the inner sides or parts of the chain belts *I*, and thereby turn the drum *G* and draw on the 5 gate-cord *O* to first lift the latch *R* and disengage it from the pin *S* at the post *C*, and then to pull the gate open on the anti-friction rollers, and after the person has passed the 10 gateway he will, by pulling on the chain *k* of the lever *K* at that side of the gate, turn the drum *G* in the other direction and wind the 15 cord *N* onto it while the gate is being closed to the post *C*, where it automatically latches to the pin *S*. One of the gate-cords *O N* uniformly winds from the drum while the other is winding onto it.

It will be noticed that the engagement of the drum-shaft sprocket-wheels by the chain belts assures the positive and easy movement 20 of the gate whenever one of the levers is operated.

Having thus described my invention, what I claim as new, and desire to secure by Letters Patent, is—

1. The combination, with posts and sliding 25 gate, the drum, cords connected with the ends of the gate, and sprocket-wheels on the ends of the drum-shaft, of two chain belts fitted to said wheels, respectively, and pivoted pull-levers *J K*, arranged in pairs on opposite sides 30 of the gate at right angles thereto, the levers of each pair being attached to the ends of a chain, as shown and described, to operate as specified.

2. The combination of the V-shaped guard 35 *T* with the sliding gate, the central post, a drum, and cords connected with the ends of the gate, the said guard being attached to the post, and its looped portion *t* extending beneath and in contiguity to the drum, as and 40 for the purpose shown and described.

HIRAM S. HARRIS.
